E. DOWNING.
AUTOMOBILE TIRE RACK.
APPLICATION FILED DEC. 1, 1916.

1,233,324.

Patented July 17, 1917.

Edward Downing Inventor
By his Attorney James Hamilton

UNITED STATES PATENT OFFICE.

EDWARD DOWNING, OF SAN FRANCISCO, CALIFORNIA, ASSIGNOR TO HGOVER SPRING CO., OF SAN FRANCISCO, CALIFORNIA, A CORPORATION OF CALIFORNIA.

AUTOMOBILE TIRE-RACK.

1,233,324.

Specification of Letters Patent. Patented July 17, 1917.

Application filed December 1, 1916. Serial No. 134,235.

To all whom it may concern:

Be it known that I, EDWARD DOWNING, a citizen of the United States of America, residing at San Francisco, in the county of 5 San Francisco and State of California, have invented certain new and useful Improvements in Automobile Tire-Racks, of which the following is a specification, reference being had to the accompanying drawings.

10 This invention relates to improvements in automobile tire-racks and particularly to improvements in the tire-racks described and shown in United States Patent No. 1150696 granted Llewelyn Arthur Nares 15 August 17, 1915, and United States Patent No. 1197272 granted me September 5, 1916; and an object of this invention is to simplify and to cheapen the construction of the tire-racks disclosed in the above-named 20 patents and to make them more efficient in operation.

In the drawings illustrating the principle of this invention and the best mode now known to me of applying that principle, 25 Figure 1 is a front elevation of the tire-rack; Fig. 2 is a section on the line 2—2 of Fig. 1; and Fig. 3 is a side elevation.

The base-ring *a* (as in the case of the base-ring of my patent hereinbefore referred to) is formed with an outwardly-projecting lip or flange *b*. To this flange *b*, there is fastened a pair of arm-hangers *c*, which are mounted at points diametrically opposite each other. By means of a pivot-pin or hinge-pin *d*, there is hingedly connected to each of these hangers *c* the inner end of a swinging arm *e*. As is clearly disclosed in Fig. 2, these hinge-pins *d* lie outside the base-ring *a* and, when the arms *e* 30 are swung into working or locking position, they are arrested and their outward travel is limited by the ring *a*. To swing the arms *e* on their pivot-pins *d*, there is provided a pair of toggle-links *f*, *f'*, which are hingedly connected to the arms *e* by pins *e* that lie within the outer ends thereof, which ends are formed with outwardly-turned lips *e'*. By "within the outer ends," it is here meant 35 that the pins *e* lie nearer the base-ring *a* than do the outer ends of the arms *e*. About midway and on the outside of each of the arms *e*, there is fastened a tire-separator *g* formed with flanges *g'*, *g''*, which, together with the flange *b* and lips *e'*, serve as stops

or rests for the tires *h*. The arms *e* are provided with facing-pieces *e''* of canvaslike material. The toggle-link *f* is bifurcated at its inner end and, between the branches *f''* of this forked end, there is held, by a lock *i*, the inner end *f'* of the toggle-link *f'*. When the lock *i* is removed and the toggle-links *f*, *f'*, are swung inwardly, their inner ends *f''*, *f''*, turn on the pivot-pin *j* formed with a head or knob *j'* to facilitate manipulation. Midway between the hangers *c*, there is fastened, to the base-ring *a*, the inner end of a tire-supporting arm *k* the outer end of which is supported by inclined braces *k'* the inner ends of which are secured to the ring *a*. The tire-rack may be mounted by fastening the 60 base-ring *a* to the bracket *m* carried by the vehicle-body *n*.

By arranging the hinge-pin connections *e* on the inside of the arm *e* and within the free end or lip *e'* of the same, the arm *e* may 65 not only be made shorter and neater in appearance but the arm *e* may also be formed with the lip *e'* and the tire is thus held in place and, at the same time, saved from wear due to the rubbing action of the outer end 70 of the arm thereagainst, when the same is manipulated.

By mounting the arms *e* within the base-ring *a* and having the flange *b* thereof extend outwardly, the latter serves as a rest 75 or stop for the inner tire and the base-ring *a* itself serves as a stop to limit the outward swing of the arms *e*. The outwardly-turned free ends *e'* of the arms *e* serve to lock the outer tire on the same, while the flange *g''* 80 of the tire-separator *g* serves the same purpose with respect to the inner tire. The flange *g'* serves as a rest or stop for the outer tire. By fastening the outer ends of the toggle-links *f*, *f'*, to the inside of the arms 85 *e* and within the outer ends thereof, the outer tire is safeguarded from wear and chafing due to the movement of the hinge-joint *e*. Again, by the provision of the tire-separators *g*, the tires are safeguarded 90 from chafing due to rubbing of the tires upon each other. Furthermore, by connecting the outer ends of the toggle-links *f*, *f'*, to the inside of the free ends of the arms *e* at a distance within the same, the pressure of 95 the toggle-links *f*, *f'*, on the arms *e* is so distributed as to be much more even, whereby 100 springing of the arms *e* near the base

ring *a* is prevented and slipping of the inner tire (which slipping would be induced by such springing) is avoided.

I claim:

- 5 1. A tire-rack including a base-ring; a pair of arms hingedly fastened thereto; and mounted free to swing within said base-ring; and a pair of toggle-links the outer ends of which are hingedly fastened to the 10 inside of said arms within the free ends thereof.
- 15 2. A tire-rack including a base-ring; a pair of arms hingedly fastened thereto at their inner ends and having their free ends formed with outwardly-turned lips that lock the tires on the arms; flanged tire-separators on the latter; and a pair of toggle-links the outer ends of which are hingedly fastened to the inside of said arms.
- 20 3. A tire-rack including a base-ring

formed with an outwardly-extending flange; a pair of arm-hangers fastened to said flange and projecting beyond said ring; a pair of arms hingedly fastened to the projecting parts of said arm-hangers and mounted free 25 to swing within said base-ring, the free ends of said arms being formed with outwardly-turned lips that secure the tires in place; and a pair of toggle-links the outer ends of which are hingedly fastened to the inside 30 of said arms.

Signed at San Francisco in the county of San Francisco and State of California, this 21st day of November, A. D., 1916, in the presence of the two undersigned witnesses. 35

EDWARD DOWNING.
